UNITED STATES PATENT OFFICE

MATTHEW H. LOUGHRIE, OF BOGOTA, NEW JERSEY, AND JOHN S. HOLLIDAY, OF NEW YORK, N. Y.; J. MARGARET HOLLIDAY, ADMINISTRATRIX OF SAID JOHN S. HOLLIDAY, DECEASED, ASSIGNOR TO MATTHEW H. LOUGHRIE, TRUSTEE, OF BOGOTA, NEW JERSEY

TRAIN-CONTROL AND CAB SIGNAL SYSTEM

Application filed November 22, 1921. Serial No. 516,945.

This invention relates to a train-control system including cab signals on the locomotive and has for an object to provide a system of this kind which will give an indication in the locomotive cab of the conditions of the block for two blocks ahead of the train and that will operate the train brakes under certain conditions of speed and block control. This invention has more particularly for its object to obtain these results by electro magnetic induction from devices on the track co-acting with devices on the locomotive. The locomotive devices comprise a novel form of vacuum electron tube which is responsive to magnetic lines of force to open or close a circuit. The track device consists of a novel type of track magnet incorporated with one of the running rails, whereby a close alignment is obtained between the locomotive devices and the track device. This invention also includes a novel type of translating device responsive to the track devices which operates the cab signal and train control apparatus without the use of relays and without the use of electrical contacts operated either electrically or mechanically. This invention also includes a novel type of manual release for the brake apparatus when it has become effective to control the train. These and other objects of the present invention are more particularly described in the following specifications and illustrated in the accompanying drawings in which Fig. 1, shows a track plan arranged for the application of this system, Fig. 2 shows an arrangement of locomotive wiring for the application of this system, Fig. 3 is a detail of the track magnet, Fig. 4 is a detail showing the construction of the vacuum tubes which it is proposed to use with this system, Fig. 4^a is a detail showing the construction of the brake valve, Fig. 5 shows a method of operating the speed control arrangement, Fig. 6 shows the details of the manual release, and Fig. 6^a shows a centrifuge used with the manual release.

Heretofore in the application of systems of this kind it has been common practice to provide relays on the locomotive responsive to the track devices which relays in turn controlled certain circuits as necessary for the application of the system. The use of relays on a locomotive and particularly on a steam locomotive is undesirable due to the excessive vibration and the extremes of temperature to which they are subjected and relays applied under these conditions are difficult to maintain and not always reliable in operation. The same conditions apply in a somewhat lesser degree to contacts operated mechanically on the locomotive. The present invention seeks to eliminate relays and contacts of any kind whatever, while at the same time obtaining all the operating results of a cab signal and train-control system. Instead of relays, electric translating devices are used, having armatures which may assume either of two positions. One of these positions represents a proceed signal while the other position represents a caution signal or speed control. These electric translating devices which are herein termed electric flippers are controlled by an arrangement of circuits hereafter to be described, according to the results desired.

No isolated track ramps or magnets are provided with this system. Instead, a track inductor in the form of a magnetic member with a winding is provided which embodies the running rail having a magnetic member placed parallel thereto and on a somewhat higher plane. This always maintains the track magnet in alignment with the running rail, introduces comparatively little obstruction on the track and enables a closer air gap to be obtained between the locomotive devices and the track magnet than is possible with an isolated track magnet.

The application of this system includes three separate sets of vacuum tube devices on the locomotive, which are responsive to the track magnet. One of these devices is arranged to give a proceed signal in response to the magnetic field of the track magnet. Another of these devices is arranged to give a stop signal in response to the outer member of the track magnet, and the third device is arranged to operate the speed control mechanism in response to the outer member of the track magnet. A double set of these devices is provided, one on each side of the locomotive and arranged to cooperatively operate the

cab-signal and train-control system as is more fully described in United States Patent #1,299,595, issued April 8, 1919.

Referring to the drawings, Fig. 1 represents a portion of track arranged for the application of this system in which 11 and 12 are the running rails, and 13 represents insulated joints dividing this track into blocks A, B and C. Each block is provided with a track battery as indicated at 14 and a track relay as indicated at 15, according to the well-known track circuit, which is the method used in the present illustration to determine whether the track is clear or blocked.

On one side of the track at the entrance to the block is placed the outer member 16 of a track magnet and on the opposite side of the track is placed the outer member 17 of a track magnet; also, where speed control is used, the outer members of the track magnets, 18, 19 and 20 are applied at intervals through the block. The track magnet included between the member 16 and the rail is magnetized by coil 21, connected by wire 22 to the common wire 23 and by wire 24 through contact 26 of the track relay 15 to the battery 27 so that when block B is clear the magnet 16 is energized, also the track magnet included between the outer member 17 and the rail is energized by coils 28 connecting on one side to wire 22, common wire 23 and on the opposite side by wire 29, contact 30 of track relay 15 for block B, wire 31 and contact 26 of track relay 15 for block C to battery 27 so that when blocks B and C are clear, this magnet is energized. The speed control magnets 18, 19 and 20 are energized by coils connecting on one side to the common wire 23 as shown and on the other side by wire 32 to wire 31 and contact 26 of relay 15 to battery 27, so that if block C is clear these magnets are energized.

The construction of the track magnet will be understood by referring to the sectional elevation shown in Fig. 3 in which the outer member is represented by the section of T-iron 42 supported by the pole pieces 41 on the core 43 of the magnet coils 21. When these coils are energized a magnetic field is set up between the rail head 11 and the T-iron 42 which have opposite polarities. The ends of the T-iron are preferably sloped or ramped with the object of offering as little obstruction as possible to apparatus depending from the train.

This invention is shown as using vacuum tube devices for responding to the track magnet. While this is the preferred embodiment of the invention it should be understood that any device or mechanism that will obtain effects on the locomotive whether inductively or by direct contact will operate the system. One type of vacuum tube proposed for this purpose is illustrated in Fig. 4. This consists of a glass tube 44 having metallic

end ferrules 45 and electrodes as shown at 46 and 47. These electrodes are metallically connected with the end ferrules 45, whereby a circuit is established through the tube between wires 122 and 123 which may be connected to a battery 101 as shown in Fig. 2. The action of this tube depends upon the ionization of an inert gas which takes place under the combined influence of a voltage applied to the electrodes and a magnetic field and thereby establishes a circuit between the electrodes. This circuit may, therefore, be interrupted by varying the magnetic field. The magnetic field is provided by means of the pole pieces 48 and 49, which, as shown, have cylindrical openings to enclose the tube.

The proceed tubes indicated by P and P¹ and shown in Fig. 3, are placed at right angles to the track and have a long pole 51 aligning with the head of the rail and a short pole 52 aligning with the T-iron of the track magnet. When the track magnet is energized the magnetic lines of force passing through these poles and through the tube, establish a circuit to give a proceed effect. When, however, the track magnet is not energized this circuit is not established. The arrangement of the stop tube differs from the proceed tube by the fact that its magnetism is supplied on the locomotive and the track device merely changes the reluctance of the magnetic circuit so as to cause an interruption of the circuit through the tube. This will be understood from the illustration showing the permanent magnet 55 applied to the poles 53 and 54 to create a magnetic field in the tube to establish a circuit. These poles are arranged to align with the T-iron of the track magnet and when passing over this iron the magnetic lines of force from the permanent magnet are conducted through poles 53 and 54 and T-iron, instead of through the tube, thus reducing the magnetic field in the tube and causing an interruption of the circuit. In the application of the speed control tube indicated by T, the poles 56 and 57 are not provided with a yoke but are provided with energizing coils 58 energized from the battery 59. This leaves an open magnetic circuit which does not create sufficient field to establish the circuit through the tube until these poles align with the T-iron on the track magnet. The T-iron forms a yoke for the poles and thereby increases the magnetic flux through the tube and thus establishes a circuit. The tubes on the left and right sides of the locomotive are identical and have corresponding reference characters. The form of vacuum tube described which responds to a magnetic field has been designated a "magnetron." Another form of magnetron applied to a train control system is disclosed in the co-pending application of Holliday, Serial No. 504,436, filed September 30, 1921.

It will be noted from the application in

Fig. 3 that the pole 51 is comparatively close to the rail head, a construction which is possible due to the fact that this pole may be carried over the rail with comparatively little variation. The short air gap thus secured enables a comparatively large air gap to be used between the pole 52 and the T-iron 42, thereby increasing the clearance so that a clearance gauge may slope off on the dotted line indicated by 50. This enables the pole 52 to be placed at such a height above the top of the rail as to prevent its conflicting with objects on the track. When a train runs over a turnout switch there will be a certain position in which the poles of the stop and speed control tubes will align with one of the running rails. The head of these rails, however, is on a lower plane than the T-iron 42, and therefore, the air gap is very materially increased, thus guarding against false operation from this cause. An additional precaution to meet these conditions can be provided by the use, at these points, of manganese rail which is non-magnetic.

25 The signal indicator is represented by 62 in the form of a semaphore arm, operated by a vertical rod 63 which connects to the walking beam 64. One end of this walking beam connects by link 65 to crank 67 of the left hand electric flipper and the opposite end connects by link 66 to crank 67 of the right hand electric flipper. These cranks are connected to the shafts of the armatures 68 which can move in either direction in the magnetic yokes 69.

30 71 represents a brake valve controlled by a magnet 72 and also by the plunger 73 connected by link 74 with the crank mounted on the shaft of the non-magnetic frame 75, carrying the coils 111 and 131 (shown in section in Fig. 2) which move within the magnetic yoke 76 and over the stationary iron core 77. On the shaft of the frame 75 the gear wheel 78 is mounted and also the 35 arm with the counter-weight 83. This wheel meshes with the pinion 79 on the shaft of motor 80. When this motor is driven the pin 81 moves around to engage the lug 82 on the frame 75 and thereby brings this into 40 position to close the valve 71 after a predetermined time interval. As soon as the motor 80 is deenergized the counterweight 83 restores the gear wheel 78 to the position shown when the action may be repeated for 45 the next operation.

50 Details of the valve in the brake pipe will be understood from the sectional drawing shown in Fig. 4^a. The valve 71 is closed when the plunger 73 is raised by the connecting link 74. Also this valve is independently closed by the core 73^a of the magnet 72 when energized, acting as a solenoid and hereafter referred to in connection with the operating circuits.

55 Attention is called to the fact that the

coils 111 and 131 being mounted on a non-magnetic yoke and moving in the field of 76 are not influenced by this magnetic field unless these coils are energized; thus, 76 being energized would not hold valve 71 closed 70 without the cooperation of coils 111 or 131 energized. The iron core 77 reduces the air gap and increases the magnetic flux through these coils.

In addition to operating the pinion 79 by 75 the motor 80, this pinion may also be operated manually from the crank 90, operating gear wheel 89, engaging pinion 88, thereby rotating disk 86 to which the centrifuge 85, is connected at 87. When the pinion 88 has 80 been brought up to sufficient speed the arms of the centrifuge 85 are spread out to engage the member 84, thereby driving pinion 79 and moving frame 75 to the position which closes valve 71. By using a centrifuge in 85 the manual release of this character, the operator must first speed up the mechanism each time he desires to reset the brake valve and it is impossible for him to leave it in any position that will hold the brake valve 90 closed.

Circuits

A source of direct current energy is provided in the battery 101 to which the common wire 102 connects on one side and the battery wire 103 connects on the other side. The circuit of the left stop tube can be traced from wire 103, tube S, wire 104, field coil 105 of 76, wire 106, field coil 107 of 69 to common wire 102. This energizes the fields of 76 and 69 in series. The proceeds circuit for the left side can be traced from battery wire 103, field coil 121 of 76, wire 122 through tubes P and P¹ in multiple circuit to wire 124, coil of armature 68 and field coil 125 of 69 to common wire 102. This energizes the fields of 76 and 69 and the armature 68 in series. The circuit controlled by the stop tube at the right side can be traced from battery wire 103, tube S, wire 108, coil 109 of 69, wire 110, moving coil 111 and wire 112 to common wire 102. This connects the field coil of 69 on the right and the moving coil of 76 in series. The proceed circuit on the right side can be traced from wire 103 to moving coil 131, wires 132 and 133 to tubes P and P¹ in multiple, wires 134 and 135 to coil of armature 68 and to field coil 136, connecting to common wire 102. This places the coil 131, armature coil 68, and coil 136 in series. The operation of this arrangement will be understood by considering the progress of a train along the track. Suppose a train passes over the track magnets 16 and 17 with the sections B and C unoccupied so that magnets 16 and 17 are both energized. The circuit controlled by the tubes S in both sides of the locomotive will be interrupted due to the deflection of the magnetic lines of 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930

force created by the magnets 55, but the proceed circuits through the proceed tubes will be established on the cab signal device so that although the coils 107 and 109 will be deenergized, the coils 125 and 136 will be energized, maintaining the signal in the clear position. In the speed control device, the coil 105 will be de-energized as will also the coil 131, but coils 121 and 111 are energized, thus 5 maintaining this device in position to hold the brake valve closed in accordance with clear track conditions. Suppose now that a train encounters the track magnets 16 and 17 and one of these magnets is deenergized and the other energized. In this case the circuit through the proceed tubes will be established on one side of the locomotive, while the corresponding circuit on the other side will not be established and the circuit from both of the 10 stop tubes will be interrupted; then only one coil of the speed control device 76 is energized and as the coils 111 and 131 are not mounted on a magnetic frame this device will move according to its bias to the position to open valve 71; also one of the electric flippers 69 will be deenergized, thus lowering one end of the walking beam 64 and giving a caution indication on signal 62. It will be found that this arrangement applies without regard 15 to which magnet 16 or 17 is energized.

Now suppose a train passes over magnets 16 and 17 when block B is occupied and both these magnets are deenergized, then the circuit is not established through either set of the proceed tubes and the circuit through both stop tubes is interrupted. This will deenergize both of the electric flippers controlling the cab signal, permitting the walking beam to move to its lowered position and giving 20 a stop indication and also will deenergize the speed control device 76 to control the train.

Suppose that a train, after receiving a stop indication as just described, encounters another set of track magnets, similar to 16 and 17 and one of these magnets is energized, then a circuit will be established through one set of the proceed tubes which will energize the armature 68 and the field 69 of one of the electric flippers and thereby bring this armature into position to raise the walking beam 64 at one end, thus giving a caution signal without, however, changing the conditions affecting the speed control device 76. Now, suppose that a train having received a stop indication, encounters track magnets 16 and 17 both energized, then the armatures and field coils of both of the electric flippers 69 will be energized. These armatures will be 25 moved to the position to raise the walking beam at both ends and thus give a clear indication and at the same time one field coil and one of the moving coils of the speed control device 76 will be energized to hold the brake valve 71 closed. In the operation of the

speed control device it will be noted that the stop tube on one side of the locomotive energizes the field and the stop tube on the opposite side energizes the moving coil, thus obtaining cooperative action between the apparatus on both sides of the locomotive. The armature 68 of the signal operating device 69 is so constructed that it will remain in the position shown when the circuit controlled by the stop tube is energized or it will remain in the position which lowers the walking beam 64 when the circuit controlled by the stop tube is energized, but it can only be moved to the position to raise the walking beam when the coil on armature 68 is also energized; that is to say, the circuit controlled by the stop tube will hold this device in whatever position it has been moved to, but this circuit in itself cannot change the position of the armature 68. On the other hand, the circuit established by the proceed tubes moves this armature to the position to raise the walking beam. When, therefore, a train passes over the space between the track magnets, the circuit established by the stop tube maintains the conditions which were established by these magnets until the next magnet is encountered. The terms, "proceed" and "stop" applied to the tubes responsive to the track devices and to the circuits, are used as a convenient designation in describing the system and are not to be understood as limited to producing the proceed and stop conditions respectively; for instance, the so-called stop circuit actually holds the apparatus in the proceed condition as the train proceeds along the track.

Speed control is obtained by an arrangement which, after a time interval, mechanically moves the moving coils carried on the frame 75 into position to close the valve 71. This is secured by a circuit established through the speed control tube on each side of the locomotive connecting in multiple circuit to the battery wire 103 and by wire 115 to the motor 80, wire 117 to magnet 72 and wire 112 to the common wire 102. This energizes motor 80 in series with magnet 72 during the time these tubes are passing over the outer member of the ramp. The magnet 72 holds valve 71 closed independently of the action of the moving coil on frame 75, so that no brake action takes place during the time a train is passing the track magnet, whether it is energized or deenergized. In this interval the motor 80 speeds up, having the pinion 79 engaging the gear wheel 78 on the shaft of frame 75. As gear 78 is rotated pin 81 moves around to engage lug 82 on frame 75, thereby mechanically moving the moving coils into position to close the valve. These coils are held in this position as soon as the circuit from the stop tubes is reestablished; that is to say, if a sufficient time interval is consumed in passing a track magnet so that

motor 80 may rotate gear 78, to move the frame 75 into position as shown, the valve 71 will remain closed after the train has passed over the track magnet and until another magnet is encountered. If, however, the train passes over the track magnet above a predetermined speed, this mechanical action will not be completed and the valve 71 will thereby be opened to control the train. When the circuit of motor 80 is deenergized, gear 78 is restored to the starting position by means of counterweight 83. This leaves the valve controlling mechanism free to respond to the movements of frame 75. It will be noted from Fig. 1 that the track magnets 18, 19 and 20 are of varying lengths and if a train encounters these track magnets deenergized, the speed at which it passes over these magnets should be progressively decreased, thereby compelling a reduction in speed as the train proceeds through the block. If, however, any of these track magnets is energized, the caution conditions which initiated the speed control are removed, a proceed signal is established and the speed control device remains in position to hold valve 71 closed.

After the speed control device has operated to control the train it is usually necessary that this device may be reset so that the train may proceed slowly through the block and for this purpose a manual release is provided operated by the crank 90, as previously described.

Attention is called to the fact that while in Fig. 1 the track magnets are shown as being energized by direct current obtained from the batteries 27, the magnetic field created by an alternating current used to energize the track magnet coils 21 will also operate this system in a manner substantially as described.

Attention is here called to the fact that this invention includes certain novel features in the construction of the track magnet; in the electron tubes responsive to the track devices; in the translating devices by which the control or signal is made effective; in the manual release and in the combination and arrangements of elements which constitute the system. Certain of the claims are directed to the novel construction of these elements and other claims are directed to the system. It should be understood that in the system claims where reference is made to the elements of the system, this reference is used in a generic sense unless specifically modified by the language of the claim. It is apparent that the electron or vacuum tubes respond to the track magnet by means of the magnetic field created by this magnet and that any arrangement producing a magnetic field will operate the system as the full equivalent of the track magnet.

Having thus described our invention, we claim:

1. In combination, a railway track, a ve-

hicle thereon, an elongated magnet on said track, one pole of said magnet consisting of one rail of said track and the other pole consisting of a ridge placed parallel with said rail, a plurality of means secured to said rail for supporting said ridge, a plurality of spaced energizing coils between said ridge and the web of said rail and a device on said vehicle responsive to both poles of said magnet.

2. In combination, a railway track, a vehicle thereon, an elongated magnet on said track, one pole of said magnet consisting of one rail of said track and the other pole consisting of a ridge placed parallel with said rail, spaced magnet coils having cores bolted to the web of said rail and secured at the opposite end to said ridge and a device on said vehicle responsive to both poles of said magnet.

3. In combination, a railway track, a vehicle thereon, an elongated magnet on said track, one pole of said magnet consisting of one rail of said track and the other pole consisting of a ridge placed parallel with said rail, said ridge placed on a higher elevation than said rail and a device on said vehicle spaced from both poles of said magnet and responsive to said magnet.

4. In combination, a railway track, a vehicle thereon, an elongated magnet on said track, one pole of said magnet comprising one rail of said track, the other pole comprising a ridge having a horizontal and a vertical member placed parallel with said rail, a plurality of energizing coils between the web of said rail and said vertical member and a device on said vehicle responsive to both poles of said magnet.

5. In combination, a railway track, a vehicle thereon, an elongated magnet on said track, said magnet having a pole placed parallel with said track, and on a higher elevation than the track and a device on said vehicle spaced from and responsive to said magnet, said device having poles of different lengths to correspond with the poles of the track device.

6. In combination, a railway track, a vehicle thereon, an elongated magnet on said track, one pole consisting of one rail of said track and the other pole consisting of a parallel ridge on a higher plane than said track, a device on said vehicle spaced from both poles of said magnet and responsive to said magnet, said device having poles located on different planes to correspond with the elevation of the poles of said track magnet.

7. In combination, a railway track, a vehicle thereon, an elongated magnet of said track, one pole of said magnet consisting of one rail of said track, the other pole consisting of a ridge placed parallel with said rail, a plurality of coils located between said ridge and said rail, said coils each having a core se-

- cured to the web of said rail and supporting brackets carrying said ridge.
8. In combination, a railway track, a vehicle thereon, an elongated magnet on said track, one pole of said magnet placed on a higher plane than the other, a device on said vehicle responsive to said track magnet, said device having poles aligning with but spaced from the poles of said track magnet, one of said poles located closer to the track magnet than the other pole. 70
9. In combination, a railway track, a vehicle thereon, an elongated magnet on said track, one pole consisting of one rail of said track and the other pole consisting of a ridge placed parallel with and on a higher plane than said rail, a device on said vehicle responsive to said track magnet, said device having poles spaced from said track magnet, one pole aligning with said rail and the other pole aligning with said ridge, the pole aligning with the rail being closer to the rail than the pole aligning with the ridge, is to the ridge. 75
10. In combination, a railway track, a vehicle thereon, an elongated magnet on said track, one pole consisting of the rail of said track and the other pole consisting of a ridge placed parallel with said rail, a device on said vehicle having a pair of poles spaced from said track magnet, one aligning with said rail and the other aligning with said ridge, said device forming a path for the lines of force between said rail and ridge. 80
11. In combination, a railway track, a vehicle thereon, an elongated magnet on said track, one pole comprising the running rail of said track, the other pole extending parallel with the running rail and secured thereto and means at intervals between the web of said rail and said parallel pole for energizing said poles. 85
12. In a train control system including a track, a vehicle thereon, a device on said track, a translating device on said vehicle having an armature capable of taking up a plurality of positions operating a signal device and a field with a plurality of energizing means with independent circuits, one of said circuits positioning said device and the other circuit holding said device in whatever position it has taken up and means for controlling said circuits from said track device. 90
13. In a train control system including a track, a vehicle thereon, a device on said track, a translating device on said vehicle, said device having a rotating armature and a field with a plurality of energizing means, one of said means positioning said armature and the other of said means holding said armature when positioned, said energizing means controlled by said track device. 95
14. In a train control system including a track, a vehicle thereon, a device on said track, a translating device on said vehicle hav- 100
- ing a rotating armature biased to a definite position, a circuit for moving said armature against said bias, a continuously energized second circuit creating a flux holding said armature in the position to which it has been moved independently of said first named circuit and means for controlling said circuits from said track device. 105
15. In a train control system including a track, a vehicle thereon, a device on said track, a translating device on said vehicle having a rotating armature biased to move to a position to control said vehicle, a circuit for moving said armature against said bias and an independent circuit creating a flux for holding said armature in either position, said circuits controlled by said track device. 110
16. In a train control system including a track, a vehicle thereon, a device on said track, a translating device on said vehicle having a field and a rotating armature, a plurality of circuits for energizing said field, said armature held in position when either of said field circuits is energized and means for controlling said circuits from said track device. 115
17. In a train control system including a track, a vehicle thereon, a device on said track, a translating device on said vehicle having a field and a rotating armature, a circuit for energizing said field and said armature and another circuit for energizing said field, said circuits controlled from said track device. 120
18. In a train control system including a track, a vehicle thereon, a device on said track, a translating device on said vehicle having a field and a rotating armature, a plurality of circuits for energizing said field and a circuit for energizing said armature, said circuits controlled by said track device, said armature biased to a predetermined position and moved against said bias when said field and armature are energized. 125
19. In a train control system including a track, a vehicle thereon, a device on said track, a translating device on said vehicle having a field and a rotating armature, a plurality of circuits for energizing said field and a plurality of circuits for energizing said armature, said armature maintained in a predetermined position when said field and armature are energized, said circuits controlled by said track device. 130
20. In a train control system including a track, a vehicle thereon, a device on said track, a translating device on said vehicle having a field and a rotating armature, a plurality of circuits for energizing said field and a plurality of circuits for energizing said armature, said circuits controlled by said track device, said armature biased to move to a predetermined position when either said field or said armature is deenergized. 135
21. In a train control system including a track, a vehicle thereon, a device on said track, a translating device on said vehicle hav-

having a field and an armature consisting of a moving coil, a plurality of circuits for energizing said armature, said armature biased to a predetermined position and held in a 5 position opposed to said bias when said field is energized and said moving coil is energized and means for controlling the circuit of said field and moving coil by said track device.

22. In combination, a railway track, a vehicle thereon, a magnet on said track, a vacuum tube device on said vehicle operating through the medium of an inert gas, a circuit connected with the electrodes of said tube, said circuit being established when said tube comes under the influence of said track magnet.

23. In combination, a railway track, a vehicle thereon, a magnet on said track consisting of one of the running rails and a parallel ridge, a vacuum tube device on said vehicle, a circuit connected to the electrodes of said tube, said circuit established when said tube comes under the influence of the magnetic field established between said ridge and rail.

24. In combination, a railway track, a vehicle thereon, a magnetic device on said track, a vacuum tube device on said vehicle, operating through the medium of an inert gas, a circuit connected through the electrodes of said tube, a magnetic field for said device on said vehicle and means for deflecting said field when said device comes under the influence of said magnetic track device.

25. In combination, a railway track, a vehicle thereon, a magnetic device on said track, a vacuum tube device on said vehicle operating through the medium of an inert gas, a circuit connected to the electrodes of said tube, a magnetic field for said tube on said vehicle and means deflecting said field when said tube comes under the influence of said track device whereby the circuit between said electrodes is interrupted.

26. In combination, a railway track, a vehicle thereon, a magnetic device on said track, a vacuum tube device on said vehicle, operating through the medium of an inert gas, a circuit connected to the electrodes of said tube, a magnetic field for said tube established on said vehicle whereby said circuit is maintained and means for deflecting said magnetic field when said tube device is under the influence of said magnetic track device to interrupt said circuit during the passage of said vehicle device over said track device.

27. In combination, a railway track, a vehicle thereon, a magnet on said track, one pole of which consists of the running rail and the other pole of which consists of a magnetic ridge, a vacuum tube device on said vehicle, operating through the medium of an inert gas, a circuit connected to the electrodes of said tube, said circuit being closed when said tube is under the influence of a magnetic field,

said tube having a pair of poles one aligning with the running rail and the other with the magnetic ridge, the pole aligning with the rail being closer to the rail than the other pole aligning with the ridge.

70

28. In a train control system the combination of a railway track, a vehicle thereon, a device on said track, a controlling mechanism on said vehicle, means for operating said controlling mechanism from said track device, a centrifuge on said vehicle and means for manually operating said mechanism by said centrifuge.

75

29. In a train control system, the combination of a railway track, a vehicle thereon, a device on said track, a controlling mechanism on said vehicle, means for operating said controlling mechanism from said track device, a device for manually releasing said mechanism by continuous motion, said device requiring an initial movement before becoming effective to operate said release and automatically resuming the non-releasing position.

85

30. In a train control system, the combination of a railway track, a vehicle thereon, a device on said track, a controlling mechanism on said vehicle, means for operating said controlling mechanism from said track device, a device for manually releasing said mechanism by rotary motion and automatically resuming the non-releasing position, said device requiring an initial movement and being operative from any starting position to operate said release.

90

31. In a train control system the combination of a railway track, a vehicle thereon, a device on said track, a controlling mechanism on said vehicle, having a shaft, means for operating said controlling mechanism from said track device, a centrifugal clutch associated with said shaft and means for operating said clutch to release said mechanism.

95

32. In a railway traffic controlling system, the combination of a railway track, a vehicle thereon, a magnet on said track, a proceed circuit and a stop circuit on said vehicle, a translating device with a magnetic field on said vehicle having a proceed and a stop position and directly connected with said circuits and means on the vehicle responding to said track magnet for controlling said circuits.

105

33. In a railway traffic controlling system the combination of a railway track, a vehicle thereon, a magnet on said track, a proceed circuit and a stop circuit on said vehicle, a translating device on said vehicle having a magnetic field energized by said circuits and having a proceed and a stop position, said proceed circuit moving said device into the proceed position and said stop circuit maintaining said device in the position to which it has been moved and means on the vehicle responsive to said track magnet for controlling said proceed circuit.

125

130

34. In a railway traffic controlling system, the combination of a railway track, a vehicle thereon, a magnet on said track, a proceed circuit, a stop circuit and a speed control circuit on said vehicle, a translating device on said vehicle having a proceed and a stop position and a translating device responding to said speed control circuit, means whereby said track magnet establishes said proceed circuit and said speed control circuit and interrupts said stop circuit.

35. In a railway traffic controlling system, the combination of a railway track, a vehicle thereon, a magnet on said track, a proceed circuit and a stop circuit on said vehicle, a translating device on said vehicle having a field energized by said proceed and stop circuits and a rotating armature with a proceed and stop position, said armature biased to the stop position when said stop circuit is deenergized and moved to the proceed position when said proceed circuit is energized and held in the proceed position by said stop circuit.

36. In a railway traffic controlling system, the combination of a railway track, a vehicle thereon, a magnet on said track, a proceed circuit and a stop circuit on said vehicle, a translating device on said vehicle having a proceed and a stop position, means for moving said translating device into the proceed position when said track magnet is energized and for moving it into the stop position when said track magnet is deenergized and means including said stop circuit for holding it in the stop position.

37. In a railway traffic controlling system, the combination of a railway track, a vehicle thereon, a magnet on said track, a proceed circuit and a stop circuit on said vehicle, a translating device on said vehicle having a proceed and a stop position and a brake control device on said vehicle, said proceed circuit and said stop circuit energizing said translating device and brake control device in series.

38. In a railway traffic controlling system, the combination of a railway track, a vehicle thereon, a magnet on said track, a proceed circuit and a stop circuit on said vehicle, a translating device on said vehicle having a proceed and a stop position and a brake control device on said vehicle connected with said circuits, said stop circuit arranged to energize said translating device and brake control device in series.

39. In a railway traffic controlling system, the combination of a railway track, a vehicle thereon, a magnet on each side of said track, devices on said vehicle cooperating with said track magnets, a proceed circuit and a stop circuit associated with each of said devices, a brake control device on said vehicle and means whereby the proceed circuit on one side, cooperating with the stop circuit on

the other side, prevents the operation of said brake control device.

40. In a railway traffic controlling system, the combination of a railway track, a vehicle thereon, a device on each side of said track, a device on each side of said vehicle responding inductively to said track device, a circuit associated with each of said vehicle devices, a translating device on said vehicle having a field and an armature, said field energized by one of said circuits and said armature energized by the other of said circuits.

41. In a railway traffic controlling system, the combination of a railway track, a vehicle thereon, a device on each side of said track, a device on each side of said vehicle responding inductively to said track device, a brake control device on said vehicle having an armature and an independent field, the circuit for said armature connected to one of said vehicle devices and the circuit for the field connected to the other of said vehicle devices.

42. In a railway traffic controlling system, the combination of a railway track, a vehicle thereon, a device on each side of said track, a device on each side of said vehicle responding to said track device, a proceed circuit and a stop circuit associated with each of said vehicle devices, a brake control device on said vehicle having a field with a plurality of windings and armature with a plurality of windings, one of said field windings controlled by the stop circuit on one side of said vehicle and one of said armature windings controlled by the proceed circuit on the opposite side of the vehicle.

43. In a railway traffic controlling system, the combination of a railway track, a vehicle thereon, a device on each side of said track, a proceed circuit and a stop circuit associated with said track device, a brake control device on said vehicle having a plurality of field windings and a plurality of armature windings, one of said field windings controlled by the stop circuit on one side of said vehicle and one of said armature windings controlled by the stop circuit on the opposite side of said vehicle.

44. In a railway traffic controlling system, the combination of a railway track, a vehicle thereon, a device on each side of said track and a circuit on each side of said vehicle controlled by said track device, a brake control device on said vehicle having a plurality of field windings and a plurality of armature windings, said field windings associated with the circuits on one side of said vehicle and said armature windings associated with the circuits on the opposite side of the vehicle.

45. In a railway traffic controlling system, the combination of a railway track, a vehicle thereon, and a magnet on said track, an inductive device on said vehicle responding to said track magnet, a brake valve on said vehicle, a speed control device on said vehicle.

operating said brake valve, a motor for operating said speed control device and means whereby a circuit is established at each track magnet which energizes said motor and brake valve.

5. 46. In combination, a railway track, a vehicle thereon, a magnet having a pair of poles on said track, a magnetic device on said vehicle having poles aligning with the poles of said track magnet and having a clearance air gap between each of the poles of said magnetic device and the poles of said track magnet, the air gap between one set of said poles being greater than the air gap between the other set of said poles.

10. 47. In combination, a vehicle control mechanism including a plurality of vacuum tube devices of which magnetic fields form controlling components and roadside mechanism including a plurality of control means, one individual to each of the devices for influencing the same in the movement of the vehicle over the roadway.

15. 48. In combination, a vehicle control mechanism including a plurality of magnetrons independently operable and combinedly controllable for operating train control circuits and roadside mechanism including a plurality of control means, one individual to each of the magnetrons for magnetically influencing the same in the movement of the vehicle over the roadway.

20. 49. In combination, a vehicle control system comprising a railway track, divided into blocks controlled by traffic conditions, devices on said track controlled by said blocks, a vehicle on said track having a device responsive inductively to said track devices, a translating device controlled by said responsive device having a proceed and a stop position and a controlling device, an electric circuit connecting said responsive device, translating device and controlling device in series and when energized causing said translating device to move to the proceed position and a second circuit on said vehicle responding to said track devices and deenergized when the block is occupied causing said translating device to move to the stop position.

25. 50. In combination, a vehicle control mechanism including a pair of vacuum tube devices of which magnetic fields form controlling components and roadside mechanism including a pair of magnet control means, one individual to each of the devices for magnetically influencing the same in the movement of the vehicle over the roadway.

30. 51. In combination, a vehicle control system comprising a railway track divided into blocks controlled by traffic conditions, devices on the trackway controlled by said blocks, a vehicle on said track having a device inductively responsive to said trackway devices, a translating device controlled by said responsive device having a proceed

and a stop position, an electro-pneumatic valve, an electric circuit connecting said translating device and vehicle device in series and when energized, causing said translating device to move to the proceed position, a second circuit associated with said translating device having an independent connection to said vehicle device and connecting said vehicle device and electro-pneumatic valve in series and means whereby one of said circuits operates in response to the track devices to cause the translating device to move to the stop position.

35. 52. In combination, a vehicle control system comprising a railway track having devices thereon controlled by traffic conditions, a vehicle on said track having a device inductively responsive to said devices, a translating device controlled by said responsive device having a proceed and a stop position and an electro-pneumatic valve, an electric circuit connecting said vehicle device, translating device and electro-pneumatic valve in series and when energized causing said translating device to move to the proceed position, and a second circuit on said vehicle connected to said responsive device responding to said track devices to deenergize said translating device and cause said translating device to move to the stop position.

40. 53. In a train control system, the combination, a railway track having magnetic devices thereon, a coil on each of said devices controlled by traffic conditions, a vehicle on said track having a device responsive inductively to said track devices, a translating device having a proceed and a stop position and an electro-pneumatic valve, an electric circuit connecting said vehicle responsive device, translating device and electro-pneumatic valve in series and when energized, moving said translating device to the proceed position, and a second circuit on said vehicle connected with said responsive device and arranged to cause said translating device to move to the stop position when the circuit of said coil is open.

Signed at New York city, in the county of New York, and State of New York, this 4th day of November, A. D. 1921.

MATTHEW H. LOUGHBRIDGE.

JOHN S. HOLLIDAY.
